UNITED STATES PATENT OFFICE.

WILLIAM S. EATON, OF SAG HARBOR, NEW YORK, ASSIGNOR TO AMERICAN BANK NOTE COMPANY, A CORPORATION OF NEW YORK.

ART OR METHOD OF CREATING INTRICATE, SYMMETRICAL, GEOMETRICAL LINE DESIGNS.

1,261,223.

Specification of Letters Patent.

Patented Apr. 2, 1918.

Application filed October 23, 1913. Serial No. 796,819.

To all whom it may concern:

Be it known that I, WILLIAM S. EATON, a citizen of the United States, residing at Sag Harbor, in the county of Suffolk and State 5 of New York, have invented certain new and useful Improvements in the Art or Method of Creating Intricate, Symmetrical, Geometrical Line Designs, of which the following is a specification, reference being had 10 therein to the accompanying drawings, which form a part thereof.

My invention relates to the art or method of creating intricate, symmetrical, geometrical line designs, and more particularly to 15 an art or method adapted to create designs suitable for use in the industrial arts.

The main object of the invention is to provide an art or method of the character herein described by means of which an intricate, symmetrical, geometrical line design 20 may be developed from a simple, elementary outline, character or base, (having, in itself, no resemblance to the created design) the design created being unique and fanciful 25 and resulting from the practice of my art or method, rather than from any predetermined intent as to, or conception of, the nature of the completed design. A further object is to provide an art or method where-

30 in a large number of dissimilar designs may be created from the same elementary outline, character or base, which designs will bear no resemblance to each other. A still further object is to provide such an art or 35 method wherein, if desired, a plurality of dissimilar designs may be simultaneously created from the same elementary outline, character or base and be superimposed one upon the other so that when creating figures 40 in the nature of a rosette, different tone values may be secured at different points of, and a distinct center design may be included in, the completed design. And a still further object is to provide an art or method of 45 the character herein described, wherein, in the completed design, the contour of the elementary outline, character or base, and the various steps in developing the design therefrom cannot be readily ascertained.

50 The invention consists primarily in an art or method of creating intricate, symmetrical, geometrical line designs, consisting in producing an elementary outline, character or base upon a master, reproducing the out-

line, character or base carried by said master upon a work plate or sheet, varying the relative positions of said master and said work plate or sheet in two directions after making said reproductions, and thereafter alternately reproducing said outline, character or base, and varying the relative positions of said master and said work plate or sheet, whereby succeeding reproductions will be spaced apart and the lines thereof will intersect each other; and in such other novel 60 steps and practices as are hereinafter set forth and described, and more particularly pointed out in the claims hereto appended.

Referring to the drawings:—

Figure 1 is a view of an elementary outline, character or base, adapted for use in the practice of my art or method; and

Fig. 2 is a representation of a fragmentary portion of a design created or developed therefrom.

In the practice of my art or method, I select an elementary outline, character or base of any desired configuration, as exemplified at *a* in Fig. 1 of the drawings, and impress it upon a master composed of any 80 substance, in a manner which will enable the operator to successively reproduce this simple figure.

By the use of the term elementary outline, character or base, I contemplate a single 85 outline forming a geometrical figure, or an incomplete geometrical figure, which in itself is simple, but which by repeated reproduction with suitable spacing, will develop a complex design, having no resemblance to 90 the base of said design.

Thereafter, I bring said elementary outline, character or base into such relation to a work plate, or sheet, as to facilitate the process of transferring said elementary outline, character or base to, or reproducing it upon, said work plate or sheet, in any desired manner, and by any desired medium.

After each reproduction of said elementary outline, character or base, I vary the 100 relative positions of said master carrying said elementary outline, character or base, and the work plate or sheet, the nature and extent of this variance being determined by the general character of the design which I 105 desire to create.

If I desire to create a straight elongated design, the relative movement of these parts

will be rectilinear; if I desire curved outlines to the created figure, and also an elongated, or polygonal figure, this movement will be curvi-linear; while if the design to be created is to have the general form of a circle, the movement will be circular; and if this figure is to have an irregular contour, the movement will be a circular movement with a radial component of motion either 10 away from or toward the center of the line of circular movement, which radial movement at different points in the creation of the design, may be varied to give an irregular contour to the created design. If, however, I desire to create a polygonal figure, I alternate a sequence of rectilinear or curvi-linear movements with a circular movement, to form the angles of such figures.

The movements in securing variances in 20 the relative positions of the master, having thereon the elementary outline, character or base and the work plate or sheet, must be step by step movements, the reproductions being alternated so as to insure exactitude in 25 the reproduction of the elementary outline, character or base, while at the same time spacing these reproductions to form a line design.

When creating designs which in their 30 contour resemble circular figures, the outline may be varied by a combined circular and radial movement; and by varying the quantity of this radial movement, two separate and distinct designs may be superimposed 35 one upon the other, one design being developed from one end of the elementary outline, character or base, and the other design from the other end thereof.

Furthermore, in developing these two designs, or in developing a single design, there 40 will be created in such a figure a center design, which is entirely distinct and apart from the other design or designs.

The angle at which the lines of succeeding 45 reproductions of the elementary outline, character or base intersect, is varied by this radial movement, and the effect is a fanciful, arbitrary design such as is illustrated at *c* in Fig. 2 of the drawings having various tone values, and one that is symmetrical throughout by reason of the fact that it 50 is built up from a single elementary outline, character or base.

The formation of one design superimposed 55 upon another is secured by positioning the elementary outline, character or base so that the major portion thereof will be upon one side or the other of the center of the circular movement, and imparting a radial 60 movement thereto which will bring the major portion thereof upon the other side of such center at different times, while the design is being created.

The elementary outline, character or base 65 will be reproduced repeatedly until an elongated

figure of the desired length has been developed, or when the feeding movement is circular, either by a step by step movement or in forming the corners of a polygonal figure, until the parts have reached the 70 starting position or have completed one entire circle, whereupon the figure is complete.

The method or art herein described has this peculiarity, that although the relative movements of the elementary outline, character or base, and the work plate or sheet may follow an outline which may be accurately or definitely predetermined, the design created by following these movements will have an outline or general configuration 80 which will bear no resemblance whatever to such outline. In fact, it is impossible to determine what the nature of the design created will be, and the same design cannot be reproduced excepting by the same sequence of movements, and the use of the same elementary outline, character or base.

In the completed design, the numerous intersections of the lines of the reproduced elementary outline, character or base make it 90 practically impossible to follow any particular line, so as to determine the character of this elementary outline, character or base, and the eccentricity of the outline will likewise make it impossible to determine the sequence of movements followed to develop any particular figure.

Where the radial movement is slight, and the elementary outline, character or base is comparatively wide at the middle, there is 100 apt to be no intersection of lines at the center, thus developing a central figure of a light tone, while if this radial movement is great, the central figure is apt to be of a dark tone or made up of lines so closely intersecting as to resemble the heavy shadows of half tone work.

I believe it to be broadly new to develop intricate, symmetrical, geometrical line designs by the repeated reproduction of an 110 elementary outline, character or base, upon a work plate or sheet, and a step by step relative movement of these two, to space the succeeding reproductions, these succeeding spacings being alternated with the reproductions of the elementary outline, character or base, and I intend to claim such broadly.

My art or method may be practised by means of a special mechanism for securing the desired relative movement of the elementary outline, character or base, and the work plate or sheet and by a special reproducing mechanism such as a pantograph, but it is not my intention to limit the practice of my art or method to any particular 125 mechanism, or any mechanism, as the same, if desired, may be practised entirely by hand, with the aid of a master bearing the elementary outline, character or base, and a work plate or sheet, and ordinary tools or imple- 130

ments for securing the desired reproduction of said elementary outline, character or base upon said work plate or sheet.

Having described my invention, what I claim as new and desire to have protected by Letters Patent, is:—

1. The herein described art or method of creating intricate, symmetrical, geometrical line designs consisting in producing an elementary outline, character or base, upon a master reproducing the outline, character or base carried by said master upon a work plate or sheet, varying the relative positions of said master and said work plate or sheet by a circular movement, and a movement radially of the axis of said circular movement, thereafter alternately reproducing said outline, character or base and varying the relative positions of said master and of said work plate or sheet by circular and radial movements, the quantity of such radial movements being varied, whereby succeeding reproductions will be spaced apart and the lines will intersect each other and create a design having an irregular contour bearing no resemblance to said elementary outline, character or base.

2. The herein described art or method of creating intricate, symmetrical, geometrical

line designs consisting in producing an elementary outline, character, or base upon a master, reproducing the outline, character or base carried by said master upon a work plate or sheet, varying the relative positions of said master and said work plate or sheet by a circular movement, and a movement radially of the axis of said circular movement, thereafter alternately reproducing said outline, character or base and varying the relative positions of said master and of said work plate or sheet by circular and radial movements, the quantity of such radial movements being varied, whereby succeeding reproductions will be spaced apart and the lines will intersect each other and create a design having an irregular contour bearing no resemblance to said elementary outline, character or base.

In witness whereof, I have hereunto affixed my signature, in the presence of two subscribing witnesses, this 2d day of October, 1913.

WILLIAM S. EATON.
